UNITED STATES PATENT OFFICE

171,399

DOLL

Dawn Howes, Suva, Fiji Islands

Application June 15, 1953, Serial No. 25,511

Term of patent 14 years

(Cl. D34—2)

To all whom it may concern:

Be it known that I, Dawn Howes, have invented a new, original, and ornamental Design for a Doll, of which the following is a specification, reference being had to the accompanying drawing, forming a part hereof.

Figure 1 is a front elevational view of a doll, showing my new design; and

Figure 2 is a side elevational view thereof.

The side not shown is like that shown in Fig. 2.

I claim:

The ornamental design for a doll, as shown and described.

DAWN HOWES.
